(57) **CLAIM**

The ornamental design for a side step for land vehicles, as shown and described.

DESCRIPTION

FIG. 1 is a perspective view of the side step for land vehicles showing my new design;

FIG. 2 is a front view thereof;

FIG. 3 is a rear side view thereof;

FIG. 4 is a left side view thereof;

FIG. 5 is a right view thereof;

FIG. 6 is a top view thereof; and,

FIG. 7 is a bottom view thereof.

The portions of the side step for land vehicles shown in broken lines form no part of the claimed design.
